HEMODIALYSIS APPARATUS

Anthony J. Carsello, Rolling Hills, Calif., assignor to
Western Gear Corporation, Lynwood, Calif., a corpora-
tion of Washington

Filed Apr. 21, 1969, Ser. No. 16,817

Term of patent 14 years

Int. Cl. D24—02; D6—01

U.S. Cl. D83—1

FIGURE 1 is a perspective view of a hemodialysis apparatus embodying my new design;

FIGURE 2 is a left side elevational view of the hemodialysis apparatus shown in FIGURE 1;

FIGURE 3 is a rear elevational view of the hemodialysis apparatus shown in FIGURE 1; and

FIGURE 4 is a top plan view of the hemodialysis apparatus shown in FIGURE 1.

I claim:

The ornamental design for a hemodialysis apparatus, as shown.
